Primary Examiner — Kendra Leslie Hamilton*Assistant Examiner* — Amanda Christensen(74) *Attorney, Agent, or Firm* — Calfee, Halter & Griswold LLP(57) **CLAIM**

I claim the ornamental design for a power pack station, as shown and described.

DESCRIPTION

FIG. 1 is a top, front, left side elevation view of a power pack station, showing my new design;

FIG. 2 is a rear, bottom, right side elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The equal-length broken lines in the drawings depict portions of the power pack station that form no part of the claimed design.

1 Claim, 6 Drawing Sheets(56)
